UNITED STATES PATENT OFFICE

WILLIAM J. RAMSEY, OF RED WING, MINNESOTA

WINDOW REFRIGERATOR BOX

Application filed December 23, 1927. Serial No. 242,229.

The present invention is directed to improvements in window refrigerator boxes.

The primary object of the invention is to provide a box of this character so constructed that it can be used in connection with windows varying in width and when in place will serve to maintain articles of food in a cool state.

Another object of the invention is to provide a device of this character so constructed that it can be easily installed for use or removed, means being provided to maintain the box in a thoroughly ventilated condition and at the same time preventing the entrance of dust or other foreign matters.

In the accompanying drawings:

Figure 1 is an elevation of the inner side of a window showing the box in place.

Figure 2 is a sectional view on line 2—2 of Figure 1.

Figure 3 is a sectional view on line 3—3 of Figure 1.

Figure 4 is a sectional view on line 4—4 of Figure 1.

Figure 5 is a sectional view on line 5—5 of Figure 1.

Figure 6 is a detail transverse sectional view through the box.

Figure 7 is a perspective view of one of the sections.

Figure 8 is a longitudinal sectional view through the device showing a double walled construction.

Figure 9 is a sectional view on the line 9—9 of Figure 8.

The device consists of two sections, 1 and 2, each consisting of a top 3, back 4, and bottom 5, and end closure 6, the section 2 having a shelf 7 suitably supported therein and upon which articles of food may be placed. The inner edges of the respective tops and bottoms of the sections are so bent as to provide grooves 8 and resultant inner and outer beads 9 and 10, the terminal flanges 11 of the beads 10 terminating in flanges 12, which not only provide a finished appearance, but add rigidity to the construction. The beads 9 have their upper walls 14 provided with a plurality of perforations 15, the purpose of which will be later explained.

It will be of course understood that the beads of the section 2 are somewhat smaller than the beads of the section 1, in order that the latter may slide within the former, thereby permitting the two sections to be telescopically connected.

Suitably secured to the forward ends of the enclosure 6 are vertically disposed casings 16 and in which are removably mounted spring restrained rollers 17 having wound thereon copper mesh screen closures 18 which serve to normally close the open sides of the sections. The free ends of the closures 18 are confined between bars 19, the upper and lower ends of which being provided with semi-circular terminals 20, constituting heads 21 for slidably engaging the upper and lower grooves 8 of the respective sections 1 and 2.

Pivotedly engaged with the bars 19 are handles 22 and to the inner ends of which are fixed blocks 23 having pivotally connected to their ends latch bars 24. These bars are adapted to selectively engage the perforations 15 to hold the closures fully closed or partly open, as desired. A coil spring 25 connects the inner bars 19 and blocks 23 and serve to urge the latch bars to their locking position, as will be obvious.

To the end closures 6 are adjustably connected brackets 26 which serve to maintain the box in proper horizontal position within the window frame.

The end closures 6 have engaged therein bolts 27 and upon which are engaged resilient bowed plates 28, there being washers 29 also engaged upon the bolts and have their peripheries engaged with the plates 28, said washers being retained on the bolt by nuts 30. As clearly shown in Figure 5, the plates 28 are engaged with the parting strips 31 of the window frame 32, it being obvious that upon adjustment of the bolts in one direction will expand the plates 28 to cause the ends thereof to bindingly engage the parting strips, thus holding the box firmly in place. When the window sash 33 is in the position as shown in Figure 2 of the drawings, access may be conveniently had to the closures 18 in order that they may be opened or closed. It will be obvious that when the sash is lowered or closed

the cold air will be permitted to enter through the closures to maintain the contents of the box in a cool state.

The construction illustrated in Figures 8 and 9, as in the other form, consists of a pair of telescopically connected sections 34 and 35. These sections are provided with double walls 36—36 and 37—37, respectively, in order to provide spaces in which an insulating medium 38 can be contained, which may be of any kind suitable for the purpose.

When a double wall construction is used it will be necessary to provide the section 34 with flanges 39 in order that the space between the sections when extended will be closed to prevent entrance of cold air into the dwelling.

Having thus described the invention, I claim:

- 20 1. A box of the class described comprising a pair of sections, the sections including a top, bottom and back, the top and bottom of each section having inner and outer beads defining a groove therebetween, the inner beads having perforations therein, said beads being adapted to slidably interfit when the sections are in telescopic relationship, spring restrained rollers carried by the sections, wire mesh closures windable on the rollers, bars fixed to the free ends of the closures and having heads for slidably engaging said grooves, latch bars carried by said bars for selectively engaging the perforations of the inner beads, and means for actuating the latch bars.
- 35 2. A window box consisting of a pair of telescopically connected sections adapted to fit in a window, said sections being provided with inner and outer beads defining grooves therebetween, the sections having open sides, flexible closures for the open sides of each section, said closures having bars carried thereby and provided with heads for slidably engaging the grooves, and means carried by the bars for engaging certain of the beads for maintaining the closures in closed or partly closed position.
- 50 3. A box of the class described comprising a pair of sections, each section consisting of top, bottom and back, the top and bottom of each section having beads defining grooves, the beads being adapted to slidably interlock when the sections are telescopically connected, rollers carried by the sections, flexible closures carried by the rollers, bars carried by the free ends of the closures, and latch bars carried by said bars for interlocking engagement with certain of the beads.

In testimony whereof I affix my signature.

WILLIAM J. RAMSEY. [L. S.]
